UNITED STATES PATENT OFFICE.

JOHN M. GINTER, OF WOOSTER, OHIO.

VULCANIZER.

1,153,059.

Specification of Letters Patent.

Patented Sept. 7, 1915.

Application filed January 29, 1915. Serial No. 5,020.

To all whom it may concern:

Be it known that I, JOHN M. GINTER, a citizen of the United States, residing at Wooster, in the county of Wayne and State 5 of Ohio, have invented certain new and useful Improvements in Vulcanizers, of which the following is a specification.

My invention relates to improvements in vulcanizers in which the vulcanizer is applied to a puncture or small tears or cuts 10 in a tube for tires.

The objects of my improvement are first, to provide means whereby the vulcanizer can be applied after the same has been properly 15 heated; second, to provide means for retaining the heat and applying the vulcanizer while in heated condition, third, to simplify the construction of vulcanizers of the class to which this belongs, and fourth, to reduce 20 the time required for the repairing of tires.

These objects, together with other objects readily apparent to those skilled in the art, I attain by the construction illustrated in the accompanying drawings, although my 25 invention may be embodied in a variety of other forms, the construction shown in the drawings being chosen by way of example.

In the accompanying drawings: Figure 1 is a vertical section showing all of the parts 30 pertaining to the vulcanizer properly connected and the same applied to a tube. Fig. 2 is a view of the vulcanizer plate and the various parts employed in heating the plate. Fig. 3 is a section taken on line 3—3, of 35 Fig. 1. Fig. 4 shows a side elevation of the assembled device upon a reduced scale.

Similar numerals of reference indicate corresponding parts throughout the several figures of the drawing.

40 In the accompanying drawings 1 represents the base or support upon which the tube, designed to be acted upon, is placed. To this base or support is attached the screw threaded bolt 2 in any convenient and well 45 known manner, either by screw threads or otherwise. The bolt 2 is provided with the wing-nut 3, which wing-nut is for the purpose hereinafter described.

The vulcanizing plate 4 is substantially 50 of the form shown in Fig. 2 and as shown it is provided with the arms or extensions 5. Located upon the base 1 and at the opposite side from the bolt 2 is a post 6 to which is pivoted the clamping ring which will be 55 hereinafter described. For the purpose of

conducting the heat into the vulcanizing plate, the said plate 4 is provided with any desired number of fingers or pins 7, which are preferably formed solid and integral with said plate. 60

For the purpose of providing proper means for heating the plate 4 by means of liquid fuel, such as gasoline, the cup 8 is provided, which cup should be formed of a size to contain sufficient liquid fuel to 65 properly heat the vulcanizing plate to a degree sufficient to vulcanize the tube acted upon. The cup 8 is held in proper spaced relationship with reference to the vulcanizing plate 4 by means of the hollow tube 9, 70 said tube being attached to the vulcanizing plate 4 by means of the screw threads 10 seated in the screw threaded socket 11. The cup 8 is attached to the opposite end of the hollow tube 9 by screw threads or otherwise, the only object being to provide proper 75 connection of the cup to the tube 9.

When it is desired to heat the vulcanizing plate 4 it, together with the different parts connected thereto, is placed in the position 80 illustrated in Fig. 2, which is in an inverted position from the position when the same is used for vulcanizing. A sufficient quantity of liquid fuel is placed in the cup 8, when said cup is in the position shown in 85 Fig. 2, and ignited, the flames moving upward against the now underside of the vulcanizing plate and against the pins 7, a sufficient quantity of liquid fuel being placed in the cup to properly heat, but not overheat the vulcanizing plate. 90

For the purpose of aiding combustion the cup 8 is provided with the short feet or lugs 12 to provide an air space between the cup and the support for said cup, and for the 95 purpose of better mingling the air with the flame whereby better combustion is provided the tube 9 is provided with the air apertures 13. The cup 8 is also provided with a series of pins or posts 14 which are formed hollow, the openings in said posts 14 extending through the cup as best illustrated in Fig. 1, whereby air is permitted to pass through said openings, thereby aiding combustion. It will be understood that air will 105 also enter the tube 9 at its open end and be drawn upward escaping through the air apertures 13. After the vulcanizing plate has been properly heated, and while hot, its position is inverted and it is placed upon 110

the tube designed to be repaired, said tube resting upon the base 1, as best illustrated in Fig. 1.

In order to retain the heat the cup 8 is 5 inclosed by means of a cover 15 which cover consists of what might be termed a cup or cap formed of a size to correspond substantially with the size of the cup 8 and to inclose portions of the fingers or pins 7, said 10 cup being held by means of an annular flange 16 upon which annular flange is seated the cup or cover 15, as best illustrated in Fig. 1, said flange 16 extending to a height sufficient to properly hold the cup 15. In use, 15 the vulcanizing plate is inverted after being properly heated and the cup placed in position.

For the purpose of retaining the heat and at the same time allowing the cup to be handled it is provided with suitable non-conducting material, preferably asbestos, which may be solid or corrugated, as shown in Fig. 3 and Fig. 1. This lining 17 is so arranged that it will not interfere with the 25 placing of the cup in the position illustrated in Fig. 1.

For the purpose of holding the vulcanizing plate firmly upon a tube or other article to be patched a clamping ring 18 is provided, said ring being provided with an arm 19 which is pivoted at 20 to the post 6. Diametrically opposite to the arm 19, an arm 21 is downwardly disposed from the ring 18, said arm having a horizontal extremity 22 which is provided with an open slot 23 which is adapted to engage the screw threaded bolt 2. Located diametrically opposite to each other and at points intermediate the arms 19 and 21 are a pair of downwardly 40 extending fingers 24 which are adapted to engage the arms 5 upon the vulcanizing plate. By this construction when the wing-nut 3 is tightened the fingers 24 firmly clamp the vulcanizing plate upon the tube which 45 is to be repaired.

It will be understood that in actual use the vulcanizing plate can be heated while it is in the position shown in Fig. 2 and when detached from the base or support 1, the 50 tube designed to be treated can be placed in proper position after which the vulcanizing plate can be placed in the position shown in Fig. 1. By this arrangement it will be obvious that the vulcanizing plate will not become over-heated during the time the tube is being repaired owing to the fact that the quantity of fuel can be regulated so that it will be entirely consumed before the vulcanizing plate is over-heated, but if in the 55 event it should be over-heated it need not be applied until the same has properly cooled and then be attached or placed in position to vulcanize the tube.

It will be understood that no tools are 60 necessary to manipulate the vulcanizing

plate other than the cup which can be held in the hand and the plate thrown on its side with the cup, after which the cup can be placed in proper position and the vulcanizing plate, together with its different attachments handled without danger by grasping the cup or cover 15.

Particular attention should be called to the fact that by means of the fireless vulcanizer herein described much time may be 70 saved in the repairing of tires which is an important item, especially when making repairs on the road. With vulcanizers heretofore commonly in use it was necessary to prepare the tire, then apply the vulcanizer, 75 then fill the fuel receptacle, light the fuel, and await the complete combustion thereof. With the present invention, however, the fuel may be placed in the vulcanizer and lighted, and while the vulcanizer is being heated the tire may be prepared for vulcanizing. By the time the vulcanizer is heated the tire will be ready to be clamped between the plates 1 and 4 and if desired the vulcanizer with the tire so clamped may 80 be placed in the machine and the journey resumed without further delay. This is also made possible by reason of the fact that the cover 15 acts as a guard to prevent the heated vulcanizing plate 4 from doing damage to any article with which it may come 85 in contact.

I claim:

1. In a vulcanizer, a base, a vulcanizing plate provided with a series of pins, means 10 for attaching said vulcanizing plate to said base, a cup provided with a series of posts having air inlets located through said posts, and an open ended hollow tube connected to said cup and vulcanizing plate.

2. In a vulcanizer, a base, a vulcanizing plate provided with a series of pins, means for attaching said vulcanizing plate to said base, a cup provided with a series of posts having air inlets located through said posts, 11 and an open ended hollow tube connected to said cup and vulcanizing plate, said hollow tube provided with apertures intermediate its ends.

3. In a vulcanizer, the combination of a 11 cup adapted to receive a supply of liquid fuel, said cup provided with a series of posts having air inlets, a hollow tube connected to said cup and open at its connected end, a vulcanizing plate provided with a series of 12 pins, said vulcanizing plate connected to said hollow tube and a cover adapted to inclose said cup.

4. In a vulcanizer, the combination of a 1 cup adapted to receive a supply of liquid 1 fuel, said cup provided with a series of posts having air inlets, a hollow tube connected to said cup and open at its connected end, a vulcanizing plate provided with a series of 1 pins, said vulcanizing plate connected to 1

said hollow tube and a cover adapted to inclose said cup, a base and means for connecting said base to said vulcanizing plate.

25

5. In a vulcanizer, the combination of a base plate, a reversible vulcanizing plate and a fuel cup, said fuel cup provided with air passages and means for holding said fuel cup and vulcanizing plate in spaced relationship with reference to each other.

30

10. 6. In a vulcanizer, the combination of a base plate, a reversible vulcanizing plate and a fuel cup, said fuel cup provided with air passages and means for holding said fuel cup and vulcanizing plate in spaced relationship with reference to each other, and a cover adapted to inclose said fuel cup.

35

15. 7. In a vulcanizer, the combination of a base plate, a reversible vulcanizing plate and a fuel cup, said fuel cup provided with air passages and means for holding said fuel

cup and vulcanizing plate in spaced relationship with reference to each other and a cover adapted to inclose said fuel cup, said fuel cup provided with a non-heat conducting lining.

8. In a vulcanizer, a base, a vulcanizing plate, arms provided upon said vulcanizing plate, a clamping ring pivotally connected to said base, fingers upon said clamping ring adapted to engage said arms, means diametrically opposite to said pivotal point and adapted to draw said clamping ring toward said base.

In testimony that I claim the above, I have hereunto subscribed my name in the presence of two witnesses.

JOHN M. GINTER.
